United States Patent Office

Des. 209,899
Patented Jan. 16, 1968

209,899

BED

Minoru Ikeda, Kokubunji-shi, Tokyo, Japan, assignor to France Bed Co., Ltd., Tokyo, Japan, a corporation of Japan

Filed Jan. 5, 1967, Ser. No. 5,324

Term of patent 14 years

(Cl. D5—4)

FIG. 1

FIG. 2

FIG. 3

FIG. 4

FIG. 5

FIG. 6

FIG. 7

FIG. 1 is a front elevational view of a bed, showing my new design;

FIG. 2 is a side elevational view thereof;

FIG. 3 is a cross sectional view thereof taken along the line A—A of FIG. 6;

FIG. 4 is a rear elevational view thereof;

FIG. 5 is a cross sectional view thereof taken along the line B—B of FIG. 6;

FIG. 6 is a top plan view thereof; and

FIG. 7 is a bottom plan view thereof.

I claim:

The ornamental design for a bed, substantially as shown.
